UNITED STATES PATENT OFFICE

RICHARD RICHTER, OF OELSNITZ/EZGB, GERMANY

SHOW CASE

Application filed March 31, 1930, Serial No. 440,348, and in Germany April 6, 1929.

This invention relates to a show-case intended for exposing to view goods of all kinds that can be housed in a show-case, and the characteristic features of the present improved show-case are these that it is composed of a plurality of individual small cases, each of which is provided with a front glass pane and with a rear wall that is adjustable with respect to said pane.

10 This subdivision of the otherwise used large front pane makes it possible to dispense with such an expensive pane, and exchanging the goods in the several compartments of the show case is facilitated; and as 15 the rear wall of each compartment is adjustable, as stated, it is possible to press the goods against the appertaining pane by means of the appertaining rear wall, whereby they are securely retained in place, and in the case 20 of such goods as, for instance, lentils, beans, peas, and the like *k*, only a very small amount thereof is necessary to make the respective compartment or compartments appear as completely filled, as the rear wall of that 25 compartment or those compartments can stand in very close proximity to the appertaining front pane or panes.

The invention is illustrated diagrammatically and by way of example on the accompanying drawing, on which Figure 1 is a front view of a show-case designed according to this invention, this case, or main case or multiple case, being composed in this example of 5 superposed compartment cases.

35 Fig. 2 is a transverse sectional view taken through the show case and showing a storage unit partially inserted within the same.

Fig. 3 is a group view of the elements forming one of my improved storage units.

40 The several compartment cases *d* are preferably housed in a common casing *a* having at its front a frame *b* by which the cases *d* are retained in said casing. There are in this latter horizontal partition walls *c* forming

45 superposed chambers, each of which can receive, and receives, a compartment case *d*.

Each of these cases consists of a rectangular frame, the size of which corresponds to the size of any one of the chambers in the casing or main case *a*, of a pane *e* firmly

fastened at the front of the compartment case, and of an adjustable rear wall or backing plate *g* which can be adjusted relatively to said pane and can be secured in its adjusted position by the elastic members *i*. The elastic members are secured to a rigid member *i'* which has its ends engaging the teeth *h*. The member *i'* can be adjusted therefore by placing it in the different teeth in order that the elastic members may have sufficient pressure to hold the rear wall or backing plate in place. The ends of this member engage ledges *n* resembling racks having ratchet teeth, and the rear wall *g* is of such proportions as to be shiftingly applied to the interior of a case, the member *i'* having, of course, been removed prior thereto and being re-inserted when the adjustment has been made.

55 There are two members *i* which are each provided with a spring, which engage in the recesses *h* in the opposite walls of the unit, whereby the rear wall *g* is yieldingly pressed against goods or articles displaced in the interspace between the glass front *e* and the rear wall *g*.

60 It is obvious that the distance between the panes and the rear walls can be varied as desired or required or best suited to the goods to be exposed to view in the individual compartments of the show-case, and that in the case of certain vegetables, as mentioned in the introductory part of this specification, only a thin layer thereof is necessary. Besides, the contents of the compartments is securely protected from dust and other impurities, and the goods enclosed between the parts *e* and *g* are held fast by them, and prevented from leaving their places. The pane *e* may be provided with a frame *f* 65 of its own inserted, of course, into the respective compartment frame *d*.

70 I claim:

75 1. A show case comprising a casing having top, bottom, side and rear walls and an open front, storage units therein, each of said storage units comprising a rectangular frame, a pane firmly fastened at the front of the frame, toothed members on the inner walls of the ends of the frame, a backing plate slid- 80

able in the frame and in position parallel with the pane and adapted to hold material to be displayed against said pane, a member having its ends anchored in the toothed members, 5 an elastic member carried thereby bearing against the backing plate for holding it in operative position, and a rectangular open frame of the same width and height as the casing and hinged thereto at one of its marginal edges, the inner portions of said last frame projecting inwardly of the side walls of the casing to engage said storage units and retain them in the casing.

2. In a device of the kind described, a storage unit including a frame having end, top and bottom walls and being open at the rear, a glass closing the front of said frame, toothed members on the inner walls of the ends of the frame, a backing plate slidable in 15 the frame and positioned parallel with the glass to hold material thereagainst, a rigid member having its ends anchored in the toothed members, and a spring carried by the rigid member and bearing against the 20 backing plate.

In testimony whereof I affix my signature.
